UNITED STATES PATENT OFFICE.

BYRON E. ELDRED, OF BRONXVILLE, NEW YORK, ASSIGNOR TO COMBUSTION UTILITIES COMPANY, OF NEW YORK, N. Y., A CORPORATION OF NEW YORK.

BLAST-FLAME FURNACE.

No. 821,994.

Specification of Letters Patent.

Patented May 29, 1906.

Application filed April 14, 1905. Serial No. 255,662.

To all whom it may concern:

Be it known that I, BYRON E. ELDRED, a citizen of the United States, residing at Bronxville, in the county of Westchester and State of New York, have invented certain new and useful Improvements in Blast-Flame Furnaces, of which the following specification and accompanying drawings illustrate the invention in a form which I now regard as the best out of the various forms in which it may be embodied.

This invention relates to furnaces or kilns for performing calcining, roasting, cintering, and similar operations upon materials, and more especially to furnaces, such as rotary furnaces, for making Portland-cement clinkers.

The object of the invention is to provide an apparatus for obtaining in the kiln a plurality of distinct regions of different temperature—that is, preferably a region of moderate temperature for calcining the cement material and a region of higher temperature for finally fusing the clinkers. This object is performed, preferably, by employing a blast-flame, such as the ordinary powdered-coal blast, or, if desired, a modified blast-flame for the main flame which occupies the body of the kiln-chamber and accomplishes the calcining or the calcining and more or less of the cintering operation, and for the final cintering or fusion of the clinkers making use of an auxiliary high-pressure gaseous jet directed transversely of the main blast and affecting a portion only of the blast-current, whereby a local current of flame is driven against the material, producing a local high temperature. This auxiliary jet may conveniently be a compressed-air jet, and for the purpose of altering its direction or the intensity of its effect upon the materials the nozzle through which it is projected may be angularly adjustable.

Of the accompanying drawings, Figure 1 represents a sectional view of a rotary kiln or furnace provided with my improvements. Fig. 2 represents an enlarged elevation of the air-regulating valve or gate for the auxiliary jet. Fig. 3 represents an enlarged elevation of the damper in the base of the stack and its operating mechanism. Fig. 4 is an enlarged elevation of the nozzles.

The same reference characters represent the same parts in all the views.

10 is the inclined rotary barrel or working chamber of the kiln with a stack 11 at the higher end and a conveyer 12 for introducing the material to the barrel at that end, a removable head 13 at the lower end, a blast-nozzle 14 supported thereon and directed nearly axial with the barrel, a receptacle or bin 15 for the powdered coal, together with suitable mechanism for feeding the coal to the blast-nozzle, and a pipe 16 connected with a fan-blower 29 and entering the rear of the nozzle for furnishing the blast-pressure and more or less of the air for combustion. These parts may all be of the usual construction and mode of operation. By reason, however, of the provision of auxiliary means for creating a high local cintering temperature, as hereinafter described, the main flame may, if desired, be modified in a suitable manner, so as to have less than its usual intensity of heating effect upon the cement material. This may be done in any well-known way or by means of diluent stack-gases, as described in a copending application, Serial No. 574,474, on which Patent No. 797,506 was granted August 15, 1905.

Above the blast-nozzle 14 an auxiliary nozzle 18 is mounted on a pivot 19 and connected by a branch pipe 20, having a flexible section, with an air-compressor 17, whereby a high-pressure jet of air is delivered against the main blast. This nozzle is directed downwardly toward the floor of the barrel 10 at an angle to the axis of the blast-nozzle, which angle may be changed by moving the auxiliary nozzle on its pivot. To regulate the pressure of the auxiliary jet, a valve 21 is shown in the branch pipe 20, having a movable pointer 22 and fixed index 23, and a pressure-gage 24 is shown connected with the branch pipe for indicating this pressure. Surrounding the nozzle 18 is a concentric nozzle 30, connected by a pipe 31, having a flexible section, with a second fan-blower 32, for furnishing a larger volume of air at a lower pressure to the auxiliary jet. By adjusting the quantities delivered by the compressor and the fan, respectively, to the auxiliary jet this jet may be given just the volume and pressure necessary to secure the best deflecting and concentrating action under the conditions of use.

In the base of the stack is an opening pro-

vided with a damper 25, which is operated by a lever 26 from near the discharge end of the kiln, whereby the center of the main flame may with ease be moved longitudinally 5 to and fro in the kiln. Opening this damper moves the flame back toward the discharge end and closing it moves it forward toward the stack. A damper 27 on top of the stack is also shown.

10 In operation the material is fed to the rotary barrel 10 by conveyer 12 and proceeds along the bottom to the discharge-chute 28 in the usual manner. The long blast-flame supported by the nozzle 14 develops within 15 the barrel and performs the calcination or driving off of carbon dioxide from the lime in the cement-forming material, and it may, if desired, be so modified in quality or effect as to perform practically no cintering 20 or only a part of the cintering usually accomplished by the body of the blast-flame. If thus modified and reduced in temperature, a useful result is secured in the way of less destructive effect upon the lining of the barrel, 25 as well as a more efficient and economical application of the heat energy of the fuel. The final high temperature required for the fusion or cintering of the cement clinkers is furnished through the agency of the auxiliary jet delivered through nozzles 18 30 and acting upon a portion only of the main blast-current, such portion being deflected downwardly upon the floor of the barrel near its discharge end and producing by agitation and 35 concentration of the combustion a localized high temperature, which makes a hard satisfactory clinker. The temperatures are thus under better control than heretofore and the heating agent more effectively applied.

40 Burning out of the lining by the cintering-flame can be minimized and avoided by the control exercised over the direction of the flame, this local flame being directed upon a portion of the floor of the barrel which is covered by cement material.

I am enabled to employ the auxiliary jet in conjunction with the ordinary apparatus for supplying blast-flames for cement burning and analogous purposes, such as the powdered-coal blast, and to secure better clinker, better control of combustion, and greater economy of fuel than has heretofore been attained.

It will be seen that the two regions of combustion are adjustable relatively to each other and each independently adjustable longitudinally of the kiln, the auxiliary flame by the pivotal movement of nozzles 18 30 and the main flame, which is more subject to the 55 draft in the kiln, by adjusting either of the dampers 25 27.

What I claim as new, and desire to secure by Letters Patent, is—

1. A furnace comprising a combustion-chamber having means for feeding material

along its floor, a blast-nozzle for projecting a flame over the material in the opposite direction to the travel of the material, fuel and blast-current connections to said nozzle, an auxiliary nozzle directed at an angle to the axis of the blast-nozzle toward the floor of the combustion-chamber and commanding a portion of the blast-current, means for supplying a high-pressure gaseous fluid to said auxiliary nozzle and means for supplying a low-pressure gaseous fluid thereto.

2. A furnace comprising a combustion-chamber, a blast-nozzle directed thereto, a receptacle for powdered coal connected with said nozzle, means to supply a blast-current 80 through said nozzle, and an auxiliary jet-nozzle commanding a portion of the blast and directed at an angle to the axis of the blast-nozzle, said nozzle comprising concentric pipes connected to different fluid sources. 85

3. A furnace comprising a rotary inclined barrel, material-supplying means at the higher end thereof, a discharge-outlet at the lower end, a blast-nozzle directed into said barrel substantially axial therewith, and an auxiliary nozzle directed across the axis of said nozzle toward the floor of the barrel, said nozzle comprising concentric pipes connected to different fluid sources. 90

4. A furnace comprising a combustion-chamber, means for producing regions of combustion of different intensities therein, and means for relatively adjusting said regions longitudinally of the furnace. 95

5. A furnace comprising a combustion-chamber, means for producing a main combustion of relatively low temperature therein, means for producing a local combustion of higher temperature, means for adjusting one of said combustions relatively to the other 100 and means for adjusting both, longitudinally of said chamber.

6. A furnace comprising a combustion-chamber, means for producing a main flame and an auxiliary flame therein, and means 110 for independently adjusting both of said flames longitudinally of the chamber.

7. A furnace comprising a combustion-chamber having means for feeding the material therethrough, a blast-nozzle at one end 115 thereof for supplying a main axial flame, means for supplying a local high-temperature flame in contact with the materials near the discharge end, and means for relatively adjusting said flames longitudinally of said 120 kilns.

8. A furnace comprising a combustion-chamber having a stack at one end, a blast-nozzle at the other end, means additional to said nozzle for producing a local high temperature at the nozzle end, and damper mechanism at the stack end for varying the position of the main-nozzle flame within the combustion-chamber. 125

9. A furnace comprising a combustion-

chamber having a stack at one end, a blast-nozzle at the other end, an auxiliary nozzle for producing a local flame, said nozzle adjustable in direction, and damper mechanism for varying the position of the main flame.

10. A furnace comprising a combustion-chamber, a main blast-nozzle, an auxiliary deflecting-nozzle having two pipes, and means for supplying fluids of different pressures through the respective pipes.

11. A furnace comprising a combustion-

chamber, a main blast-nozzle, an auxiliary deflecting-nozzle having outer and inner pipes, an air-compressor connected with the inner pipe, and a fan-blower connected with the outer pipe.

In testimony whereof I have hereunto set my hand, in the presence of two subscribing witnesses, the 8th day of April, 1905.
